UNITED STATES PATENT OFFICE.

WILLIAM DUNCAN REID, OF WOOLLAHRA, NEAR SYDNEY, NEW SOUTH WALES,
AUSTRALIA.

KIT BAG, TRAVELING BAG, AND THE LIKE.

Application filed April 2, 1924. Serial No. 703,611.

To all whom it may concern:

Be it known that I, WILLIAM DUNCAN REID, a subject of the King of Great Britain, residing at Woollahra, near Sydney, in the State of New South Wales, Commonwealth of Australia, have invented new and useful Improvements in Kit Bags, Traveling Bags, and the like, of which the following is a specification.

10 This invention relates to improvements in hand-bags, and more particularly to improvements in hand-bags of that type known as kit-bags, which are provided at their top portions with collapsible frames adapted to fold together and extend longitudinally along the centre of the top of the bag when the same is closed, and having an appropriate handle and end closure devices.

20 The capacity of a hand-bag of the character indicated is limited by the necessity of making space provision to enable the frames to be collapsed and the upper portion of the bag to be downwardly and inwardly folded, which are now required to be performed before the bag can be closed and locked.

25 The present invention provides a kit-bag, which can be used exactly in the same manner as ordinary kit-bags now in use, but equipped with means whereby the upper portion of the bag can be fully extended to augment the carrying capacity of the bag, when the bag can be closed and locked in such extended position, thus increasing the range of use and general utility of the bag.

30 A kit-bag according to my improvements is characterized by the provision of an independent collapsible cover attached to the side walls of the bag and to slidable closure bars. This cover is arranged so as to fold 35 interiorly of the bag when the frames thereof are collapsed in the manner of ordinary use of kit-bags, and it is also adapted to be stretched horizontally to provide a cover proper for the bag when the same is extended to augment its carrying capacity.

40 Reference is had to the accompanying drawings, wherein:—

45 Figure 1 is a side elevation of a kit-bag constructed according to my improvements,

the bag being collapsed and having the same 50 dimensions, configuration and carrying capacity as that of an ordinary kit-bag.

Figure 2 shows in side elevation the kit-bag when extended to augment its carrying 55 capacity.

Figure 3 is a view in plan of Figure 1.

Figure 4 is a view in plan of Figure 2.

Figure 5 is a view in plan of the kit-bag with its top frame open to facilitate the 60 packing of articles in said bag.

Figure 6 is an end elevation of Figure 1.

Figure 7 is a view in end elevation of Figure 2.

Figure 8 is a detail sectional view illustrating one of the hinged frame members 65 functioning as runners slidably supporting the frame closure bars.

Figure 9 is a sectional plan view on line A—A of Figure 8.

Figure 10 is a detail sectional view illustrating means for closing the bag when the same is fully extended.

Figure 11 is a view in plan of an end of the bag while being closed.

Figure 12 illustrates in side elevation one 75 of the frame closure bars slidably mounted upon the hinged frame or runner bars, said closure bar being equipped with a lock, handle and end clip devices.

In the embodiment of the invention illustrated in the drawings there is provided a body portion substantially of rectangular shape comprising a bottom and side walls 1 constructed of stiff leather or other suitable material, and each side wall 1 being extended, as at 2, and adapted to be folded inwardly over the opening to the body to constitute a part of a closure for the bag. The end walls 3 are constructed of the same material as the side walls and each end wall at 80 its upper end has an extension 4 of pliable material, such as light leather, secured thereto to also constitute a part of the closure for the opening of the bag. The extended portions 2 of the sides 1 and the extended portions 4 of the ends 3 are secured together at 85 their edges as by stitching.

90 A frame is secured to the edge portions

of the extensions 2 and 4 of the sides and ends which is constructed and arranged to maintain said extensions extended when the bag is opened and to be collapsed to fold the extensions 2 over and the extensions 4 inwardly of the opening of the bag to close the same. This frame comprises a pair of bars 7 of angle shape in cross section to constitute the side members of the frame, one bar being secured in a suitable manner to each of the edge portions of a side extension 2, in the present instance by interposing the same between one side of an angle portion of a bar and a plate 7' secured thereto by riveting, as at 6. The end members of the frame comprise a pair of sections 5 and 5^a of angle shape in cross section pivotally or hingedly connected, as at 16, which connection is disposed at the longitudinal center of the bag whereby said sections may be folded in a direction into and longitudinally of the body of the bag and arranged to have a limited outward movement. The opposite ends of the sections of the end bars are pivotally connected adjacent to the ends of said bars by means of lugs fixed to the side bars, as shown at 17. To limit the outward movement of the sections of the end bars of the frame an angle portion of one of the end frame members, in the present instance the section 5^a, has one of its longitudinal edge portions bent upon itself to U or channel shape in cross section, as at 5^b, and the other sections 5 are arranged with a recess 5^c by cutting away a portion of the edge of the one angle portion to a depth substantially the thickness of the material of the bar sections, and the end wall of which recess is adapted to abut against the end wall of channel portion 5^b of the other bar section when the bar sections are extended. The end bars of the frame are secured to the edge portion of the extension 4 of the ends of the bag body by interposing said edge portions between an angle portion of the bar sections similar to securing the side bars of the frame to the side extensions by plates 5' and riveting the plates to the end bar sections. By this arrangement to close the bag the hinged sections of the end bars are collapsed by exerting a force thereon to move them in a direction into and longitudinally of the bag breaking the jointed connection of the bar sections and then by exerting pressure on the side bars of the frame in a direction toward each other thereby moving the hinged sections of the end bars to lie substantially in parallel relation to each other and the side bars of the frame drawing the side extensions 2 over the open end of the bag and the end extensions 4 inwardly beneath the side extensions as shown in Figure 3. To open the bag all

that is necessary is to draw the side bars 7 outward thereby moving the sections of the end bars to extended position and when fully extended said bars maintain the side and end portions of the bag in open position.

To secure the frame collapsed and the bag in closed condition a pair of closure bars 9 and 10 are provided. These bars are of angle shape in cross section and slidably mounted upon the sections 5, 5^a of the end members of the frame (for a purpose to be hereinafter described) by forming elongated slots 18 (Figure 12) in the ends of said bars to slidably accommodate said sections. The bar 10 is of comparatively narrow width as compared with the bar 9 so that said latter bar will engage over and conceal the bar 10 when the closure bars are moved to closing position with the bars 7, as shown in Figure 3. To secure the bars 9 and 10 in closed position the bar 10 is arranged with hasps 12 to engage in openings in a lock casing 13 fixed to the inner side of the bar 9 to be engaged by the lock bolt therein. The outward movement of the bars 9 and 10 on the sections 5, 5^a of the end bars of the frame is limited by engaging abutments 8 at the ends of said bars 7 in the form of lugs stamped from the material of the side bars. To facilitate the collapsing or folding of the bar sections 5, 5^a inwardly to fold the side and end extensions 2 and 4 to close the bag in the ordinary manner for use in its normal carrying capacity as shown in Figures 3 and 6, the bars 9 and 10 are arranged with guideways 20 for receiving said bar sections 5, 5^a. In the arrangement shown these guideways are formed by securing a bar 19 of angle shape in cross section to the inside surface of the depending angle portion of each of the bars 9 and 10 with the horizontal webs of the bars 19 and the closure bars in spaced relation as clearly shown in Figure 12.

When the side and end extensions 2 and 4 are in extended position by maintaining the frame members 7, 5 and 5^a in extended position, to increase the capacity of the bag, as shown in Figures 4 and 7, there is provided an auxiliary closure for the extended open end of the bag. This auxiliary closure comprises sheets or strips of pliable material 11, such as leather or the like, one sheet being secured at one longitudinal edge portion to the closure bar 9, as at 11^a, and the other sheet secured to the closure bar 10, as at 11^b, the sheets 11 at the opposite longitudinal edge portions being secured to the side frame members 7, as at 11^c (Figure 9). When the bag is closed in the ordinary manner as shown in Figures 3 and 6 by collapsing the frame members 7, 5 and 5^a as hereinbefore described, these sheets 11

- are folded against the interior of the side extensions 2. However, when the bag is to be closed by said sheets 11 when the frame members 7, 5 and 5^a are extended as shown, 5 in Figures 4 and 7, the closure bars 9, 10 are slid or moved along the sections 5, 5^a of the end bars of the frame and drawing therewith the sheets 11 over the opening to the bag and closing the same. The 10 closure bars 9, 10 are secured in closed position by the hasps 12 engaging the lock 13. In this closing position of the closure bars they engage over the joint of the pivot or hinged connection of the sections 5, 5^a of 15 the end bars of the frame firmly holding said bar sections against collapsing.
- To carry the bag it is provided with a hand grip 14 connected to the closure bar 9. To further secure the closure bars in 20 closed position clips 15, which may be of conventional form, are pivotally carried by the bar 9 to be engaged over the ends of the closure bars and extend around the sides thereof.
- 25 The ends of the closure bars 9 as well as the ends of the sections 5, 5^a of the end frame members are bent downwardly to enhance the appearance thereof, and also to prevent the exposure of rough edges which 30 may catch in and damage the apparel of the user of the bag.
- To facilitate the opening of the bag a metal pull ring 21 is secured to the outer side of one of the side members of the 35 frame.
- What I do claim is:—
1. In a kit-bag or like hand-bag having hinged collapsible end bars, an element 40 slidable on said end bars functioning as a closure for the bag when the upper portions thereof are vertically extended.
  2. In a kit bag, or like hand bag, a body portion, a frame secured to the edge portions 45 of the opening of the bag having hinged end portions adapted to be collapsed in a direction longitudinally of and into the bag in one closing position of the bag, and to be maintained extended in another closing position of the bag, and an auxiliary cover 50 element to serve as a closure for the bag in said latter position of the hinged bars, and said auxiliary cover element adapted to be folded interiorly of the bag when the bag is closed with the end bars collapsed.
  - 55 3. In a kit-bag or like hand-bag having hinged collapsible end bars, bars slidable on said hinged end bars when the same are extended, lock elements carried by said slidable bars, and closure elements secured 60 at one end to the bag body and at their opposite ends to said slidable bars.
  4. In a kit-bag or like hand-bag having end frame bars hingedly connected together at the longitudinal centre of the bag, longi- 65 tudinal frame members affixed to the side walls of the bag at the top thereof, bars slidable on said end bars, and pliable closure strips carried by said slidable bars.
  5. In a kit-bag or like hand-bag having hinged collapsible end bars, bars slidable 70 on said hinged end bars when the same are extended, lock elements carried by said slidable bars, longitudinal frame members secured to the walls of the bag, closure elements secured at one end to said frame 75 members and at their opposite ends to said slidable bars, and lugs on said frame members limiting the outward movement of said slidable bars.
  6. A kit-bag or like hand-bag having 80 longitudinal frame members affixed to its side walls, end bars hingedly connected together at their inner ends and hingedly secured at their outer ends to said frame members, means limiting the outward movement 85 of said hingedly connected bars, bars slidable on said hinged bars when the same are extended, slots in said slidable bars accommodating said hinged bars, lock devices mounted on said slidable bars, a handle and 90 end clips secured to one of said slidable bars, and means limiting the outward movement of said slidable bars.
  7. A kit-bag or like hand-bag having 95 hingedly connected and infolding end bars, angle-section bars slidable on said end bars when the same are extended, bag closure elements secured to said slidable bars, angle-section bars fitted to said slidable bars providing a guideway for said end bars when 100 infolded, lock devices mounted on said slidable bars, and a handle on one of said slidable members.
  8. In a kit bag or like handbag, a body portion, a frame secured to the edge portions 105 of the opening of the bag having hinged end portions adapted to be collapsed in a direction longitudinally of and into the bag in one closing position of the bag, and to be maintained extended in another closing position of the bag, an auxiliary cover element to serve as a closure for the bag in said latter position of the hinged bars, and said auxiliary cover element adapted to be folded interiorly of the bag when the bag is closed 110 with the end bars collapsed, and means for securing the bag in either of its closed positions.
  9. In a bag, a body portion having ex- 115 tended side and end portions, a frame secured to an edge portion of said side and end extensions, opposite bars of said frame being collapsible in a direction into and in a plane parallel to the top of the body portion, and said frame bars when in extended position adapted to maintain the extended side and end portions in open and extended position, closure bars mounted on said frame 120
  - 60 125

to have movement toward and away from each other, an auxiliary closure sheet secured at one edge portion to each of the closure bars and at the opposite edge portion to the frame, said auxiliary closure sheets adapted to be folded to the interior of the side extensions of the body when the bag is closed with the frame collapsed, and said closure bars adapted to be moved along

the frame when the bag is closed with the 10 side and end extensions of the body extended and draw the auxiliary closure over and close the opening of the bag.

In testimony whereof I affix my signature in the presence of a witness.

WILLIAM DUNCAN REID.

Witness:

M. STARFIELD.
